UNITED STATES PATENT OFFICE.

HAROLD G. NILSON, OF KALAMAZOO, MICHIGAN.

SELF-HEATING CURLING-IRON.

1,069,164.

Specification of Letters Patent.

Patented Aug. 5, 1913.

Application filed November 29, 1912. Serial No. 734,099.

To all whom it may concern:

Be it known that I, HAROLD G. NILSON, a citizen of the United States, residing at 608 Arcadia Court, Kalamazoo, Michigan, have 5 invented certain new and useful Improvements in Self-Heating Curling-Irons, of which the following is a specification.

This invention relates to improvements in self-heating curling irons.

10 The main objects of this invention are,— First, to provide an improved self-heating curling iron having an igniting means which is very simple and convenient in its operation. Second, to provide an improved self-heating 15 curling iron adapted for the use of liquid fuel such as alcohol or gasoline or other hydrocarbons, which may be placed in any position while charged with fuel without danger of the fuel's spilling or leaking. Third, 20 to provide an improved self-heating curling iron which has the above advantages, which is very quickly heated.

Further objects, and objects relating to structural details, will definitely appear 25 from the detailed description to follow.

I accomplish the objects of my invention by the devices and means described in the following specification.

The invention is clearly defined and 30 pointed out in the claims.

A structure which is a preferred embodiment of my invention is clearly illustrated in the accompanying drawing forming a part of this specification, in which:

35 Figure I is a side view of my improved self-curling heating iron mounted upon its support. Fig. II is a detail view mainly in vertical central section. Fig. III is an enlarged detail view in vertical central section showing details of the fuel feed chamber, the feed valve, the wick holder and igniter. Fig. IV is an enlarged detail vertical section through the lower portion of the 40 hand piece, the valve finger piece, and the support. Fig. V is a transverse section on a line corresponding to the broken line 5—5 of Fig. III. Fig. VI is a transverse detail section on a line corresponding to line 6—6 of Fig. III. Fig. VII is an enlarged detail 45 section through the valve, on a line corresponding to line 7—7 of Fig. III. Fig. VIII is a transverse section on a line corresponding to line 8—8 of Fig. II.

In the drawing similar reference characters refer to similar parts throughout the several views, and the sectional views are

taken looking in the direction of the little arrows at the ends of the section lines.

My improved self-heating curling iron as embodied in the structure illustrated, comprises a hand piece 1 having a fuel reservoir 2 therein,

The tubular curling rod member 3 is tapered toward its outer end and is provided with a fuel feed or wick chamber 4 at its 65 inner end or base. The chamber 4 is open at the bottom, its outer end being closed by the wall 5 having a wick holder 6 thereon.

The curling rod member 3 is removably mounted on the hand piece, being preferably 70 shouldered at 7 and threaded into the hand piece at 8.

The wick 9 is arranged in the wick holder 6, its lower end being surrounded by the absorbent material 10 within the feed chamber. 75

The end wall 11 of the reservoir 2 is provided with a valve seat 12 for the conical valve 13. The valve stem 14 of the valve 13 is arranged longitudinally through the 80 fuel chamber and provided with a finger piece 15 threaded into the lower end of the hand piece.

By adjusting the finger piece, the valve is 85 opened or closed. The valve is provided with a shank 16 having a tongue 17 arranged in a slot 18 in the end of the stem, the shank being secured by the pin 19 engaging a slot 20 in the stem. This permits a limited longitudinal movement of the shank 90 in the stem.

A sleeve 21 is carried by the stem and embraces the joint between the shank and the stem. On this sleeve is a coiled spring 22 acting against the valve to hold it yieldingly 95 in its seat. The object of this is to permit contraction and expansion of the metal as it is heated and cooled without straining the parts and without opening the valve.

The finger piece 15 is provided with passages 23 normally closed by the plug 24. This plug is provided with a socket 25 for the nipple 26 on the cup-like support 27. This support 27 is adapted as a funnel for filling the reservoir, and also as a support. 100 105

The clamping member 28 is pivoted at 29 on the arm 30 carried by the curling rod member 3. The spring 31 holds the clamping member normally closed.

A lighting device comprising the abrad- 110 ing wheel 32 mounted on the support 33 and the block of pyrophoric material 34, is

provided. The support 33 is mounted on the curling rod member 3 opposite the clamp member 28. The pyrophoric block 34 is yieldingly supported by the coiled spring 35, the adjustment of the tension of the spring being effected by the screw 36.

5 The member 3 is provided with air inlet openings 37 about the wick holder, and with an opening 38 opposite the sparking device, so that when the abradent 32 is rotated, the 10 sparks are thrown through the opening across the wick.

15 The member 33 is provided with an opening 39 opposite the opening 38, the opening 39 being considerably larger than the opening 38 and extending some distance toward the end of the member 3.

20 In use, the valve 13 is opened to admit a quantity of the fuel into the fuel feed chamber and is then closed. The fuel is taken up by the absorbent material and by capillarity 25 passes out through the wick. Gasolene or like fuel is preferably used as it readily volatilizes so that it may be quickly ignited by means of the sparking device.

25 In igniting, the clamp member is preferably held open until a brisk blaze is secured. The arrangement of the openings 38 and 39 described, tends to carry the heat away from 30 the igniting device and up the clamp member and the curling rod.

35 The device may be used a number of times without refilling the reservoir and can be packed or transported without danger of spilling the fuel.

40 I have illustrated and described my improved self-heating curling iron in detail in the form in which I have embodied the same. I have not attempted to illustrate 45 or describe the various modifications which I contemplate as such modifications will no doubt be readily understood by those skilled in the art to which this invention relates. I desire, however, to be understood as claiming my improvements specifically in the form illustrated, as well as broadly within the scope of the appended claims.

50 Having thus described my invention, what I claim is new and desire to secure by Letters Patent is:

55 1. In a self-heating curling iron, the combination of the hand piece having a fuel reservoir therein, a tubular curling rod member removably mounted on said hand piece, said member being open at its outer end and provided with a wick chamber at its inner end open at the bottom, there being a valve in the upper end wall of said hand piece reservoir for admitting fuel to 60 said wick chamber, a pivoted clamping member mounted on said curling rod member to coat therewith, and a sparking device mounted on said curling rod member opposite said clamping member, said curling rod member being provided with air in-

let openings above said wick chamber and with an opening in front of said sparking device and with a larger opening on its clamping member side extending upwardly above said sparking device opening.

70 2. In a self-heating curling iron, the combination of the hand piece having a fuel reservoir therein, a tubular curling rod member removably mounted on said hand piece, said member being open at its outer end and provided with a wick chamber at its inner end open at the bottom, there being a valve in the upper end wall of said hand piece reservoir for admitting fuel to said wick chamber, a wick holder in the top wall of said wick chamber, and a pivoted clamping member mounted on said curling rod member to coat therewith.

75 3. In a self-heating curling iron, the combination with the hand piece having a fuel reservoir therein, a tubular curling rod member, there being a wick chamber at the inner end of said curling rod member, a valve for admitting the fuel from said reservoir to said wick chamber, a wick holder, a clamping member coacting with said curling rod member, and a sparking device mounted oppositely of said clamping member, said curling rod member being provided with an opening in front of said 80 sparking device and with a larger opening on its clamping member side extending upwardly above said sparking device opening.

85 4. In a self-heating curling iron, the combination with the hand piece having a fuel reservoir therein, a tubular curling rod member, there being a wick chamber at the inner end of said curling rod member, a valve for admitting the fuel from said reservoir to said wick chamber, a wick holder, 90 and a clamping member coacting with said curling rod member.

95 5. In a self-heating iron, the combination with the hand piece provided with a fuel reservoir, a tubular curling rod member, a wick holder at the base of said curling rod member, a clamping member coacting with said curling rod member, and a sparking device mounted oppositely of said clamping member, said curling rod member being provided with an opening in front of said 100 sparking device, and an opening on the clamping member side.

105 6. A self-heating curling iron comprising a hand piece having a fuel reservoir therein, a tubular curling rod member, a fuel feed chamber, a valve for admitting fuel from said reservoir to said feed chamber, a clamping member coacting with said curling rod member, and a sparking device mounted oppositely of said clamping member.

110 7. A self-heating curling iron comprising a hand piece having a fuel reservoir therein, a tubular curling rod member, a fuel feed chamber, a valve for admitting fuel from 115

said reservoir to said feed chamber, and a clamping member coacting with said curling rod member.

8. A self-heating curling iron comprising in combination, a hand piece having a fuel reservoir therein, a tubular curling rod member removably mounted on said hand piece, said member being open at its outer end and provided with a wick chamber at its inner end open at the bottom, there being a valve in the upper end wall of said hand piece reservoir for admitting fuel to said wick chamber, and a wick holder in the top wall of said wick chamber, said curling rod member being provided with air inlet openings above said wick chamber.

9. A self-heating curling iron comprising in combination, a hand piece having a reservoir therein, a feed chamber at the inner end of said fuel reservoir, a valve controlling the delivery of fuel from said reservoir to said feed chamber provided with a stem disposed longitudinally of said wick chamber, a finger piece for said valve stem threaded into the outer end of said hand piece and having a filling opening therethrough, a plug for said filling opening having a socket in its outer end, a cup-like support provided with a nipple adapted to be inserted in said filling opening for filling the reservoir or to be inserted in said seat for supporting the curling iron in an upright position.

10. A self-heating curling iron comprising in combination, a hand piece having a reservoir therein, a feed chamber at the inner end of said fuel reservoir, a valve control-

ling the delivery of fuel from said reservoir to said feed chamber provided with a stem disposed longitudinally of said wick 40 chamber, and a finger piece for said valve stem threaded into the outer end of said hand piece.

11. A self-heating curling iron comprising in combination, a hand piece having a reservoir therein, a feed chamber at the inner end of said reservoir, a valve controlling the delivery of fuel from said reservoir to said feed chamber and provided with a stem disposed longitudinally of said wick chamber 50 50, a finger piece for said valve stem threaded into the outer end of said hand piece, there being a pin and slot connection for said valve to said valve stem, a sleeve on said valve stem embracing said connections, 55 and a spring arranged on said sleeve.

12. A self-heating curling iron comprising in combination, a hand piece having a reservoir therein, a feed chamber at the inner end of said reservoir, a valve controlling 60 the delivery of fuel from said reservoir to said feed chamber and provided with a stem disposed longitudinally of said wick chamber, said valve being yieldingly supported on said valve stem, and a finger 65 piece for said valve stem threaded into the outer end of said hand piece.

In witness whereof, I have hereunto set my hand and seal in the presence of two witnesses.
